COLLAPSIBLE FORM OR MOLD

William Theodore Hardy, deceased, late of Dallas,
Tex., by Myrtle Hardy, administratrix, Dallas,
Tex.

Application November 2, 1936, Serial No. 108,879

3 Claims. (Cl. 25—131.5)

This invention relates to a collapsible form or mold for the building of culverts, drainage or storm sewers, bridges or tunnels or for any other purpose for which the form is applicable.

5 The object of the invention is to provide, in a manner as hereinafter set forth, a form consisting of a series of re-usable, separate elements capable of being expeditiously assembled and disassembled when occasion requires.

10 A further object of the invention is to provide, in a manner as hereinafter set forth, a form consisting of a series of re-usable, separate elements of any suitable material such as metal or wood and with the elements so constructed as to enable the assembling thereof in forming or molding position without the employment of driven holdfast devices entering said elements.

15 A further object of the invention is to provide, in a manner as hereinafter set forth, a form or mold including a pair of oppositely disposed releasably interengaging body sections and a pair of oppositely disposed removable wedge-like sill elements for jacking up the body sections in interengaged relation.

20 A further object of the invention is to simplify the use and construction of forms, whether they be made of wood or metal, for the building of culverts, drainage, or storm sewers, bridges and tunnels of any size opening; for reducing the cost of operation; and for increasing the efficiency and rendering them easier to be manipulated, thereby saving time, trouble and money for those who desire to build culverts, drainage or storm sewers, bridges and tunnels of any size 25 opening.

25 To the above ends essentially and to others which may hereinafter appear, the invention consists of the novel construction, combination and arrangement of parts as will be more specifically described and are as illustrated in the accompanying drawing wherein is shown an embodiment of the invention, but it is to be understood that changes, variations and modifications may be resorted to which fall within the scope of the 30 invention as claimed.

In the drawing:—

35 Figure 1 is an isometric view of the form broken away showing the interior thereof,

40 Figure 2 is an end view of the form prior to the complete jacking-up of the body sections,

45 Figure 3 is an end view of the form with the body sections completely jacked up and with the form shown in position for forming the super-50 portion of a tunnel upon the bottom of the latter and with the tunnel indicated in dotted lines,

5 Figure 4 is a top plan view of the sill elements disposed in jacking-up position in full lines and in dotted lines removed from such position by a projecting and retracting tool,

5 Figure 5 is a side elevation of the form of removable combined coupling and bracing element employed for the body section,

10 Figure 6 is a view similar to Figure 5 of the form of removable combined coupling and bracing members employed for the sill elements, and

15 Figure 7 is a perspective view of the sill projecting and retracting tool.

20 A collapsible form or mold, in accordance with this invention includes a pair of oppositely disposed body sections 8, 9, a set of combined coupling and bracing elements 10 for the body sections 8, 9, a pair of oppositely disposed sill elements 11, 12 substantially of the same length as that of the body sections, and a pair of combined coupling and bracing members 13, 14 for the elements 11, 12.

25 The body sections 8, 9 are to be of the desired length, width and height depending upon the size of the structure to be formed.

30 The body section 8 includes a plurality of up-standing parallel spaced internal ribs or supports 15 of like form. Each rib 15 consists of a body part 16 of the desired width, thickness and height, disposed on its bottom edge 17. The body part 16 includes a straight outer side edge 18, a rounded upper edge 19 extending inwardly from its lower to its upper end, and an inner side edge. The latter is formed of an upper and a lower straight edge portion 20, 21 respectively disposed 35 in parallel endwise spaced relation and separated by an inwardly extending V-shaped edge portion 22 having one end merging into the lower end of edge portion 20 and its other end merging into the upper end of edge portion 21. The inner side 40 edge also includes an edge portion 23 inclining in a direction towards edge 18 and merging at its lower end into the inner end of edge 17. The upper end of edge portion 23 merges into the lower end of edge portion 21. The edge portions 45 20, 21 are of the same length. The edge portion 24 is of greater length than edges 17, 18 and 19. The inner end of edge 17 is arranged above the lower end of edge 18. The edge 17 inclines 50 downwardly from its inner end to the lower end of edge 18. Owing to the manner in which the edges of the rib 15 are set up, the rib increases in width from its bottom to its top. The V-shaped edge portion 22 provides a groove on and near the upper end of the inner edge of the rib. The latter near its lower end and in proximity to

55

edge 17 is formed with an opening 24. Secured to the edges 18 of the ribs 15 is a cheek plank 25 disposed on its bottom edge and with the latter inclined at the same inclination as and forms a flush continuation of the bottom edge 17 of rib 15. Secured to the edges 19 of the ribs 15 are abutting crown planks 26.

The body section 9 is constructed in the same manner as the body section 8 with this exception that the ribs or supports 27 of section 9 are provided on their inner edges with V-shaped extension 28, in lieu of the V-shaped inner edge portion 22 which provides the groove. When the body sections are set up in oppositely disposed relation, 15 the extensions 28 are seated in the grooves formed by the V-shaped edge portions 22. Otherwise than that as stated, the construction of body section 9 and its ribs 27 will be the same as that of body section 8. The openings in ribs 27 are 20 indicated at 29. The cheek plank and the crown planks of body section 9 are indicated at 30, 31 respectively. The outer side edge, top edge, bottom edge and inner side edge of the ribs 27 are indicated at 32, 33, 34 and 35 respectively.

25 Each combined coupling and bracing element 10 is of yoke-shaped contour and is formed of a metallic rod having its end terminal portions 36, 37 disposed at right angles to its intermediate portion 38. The latter is of materially greater length than the portions 36, 37.

The sill elements 11, 12 are of like form and each consists of an elongated bar 39 of wedge-shaped contour. The bar 39 has a flat bottom face 40, an outer side edge 41, an inner side edge 42 of greater height than the edge 41 and an upper face 43 inclining downwardly from edge 42 to edge 41. The inclination of the upper face 43 of a sill corresponds to that of the bottom edge of a rib. The sill 11 is formed with a pair of spaced aligned openings 44, 44^a. Each opening is arranged between the transverse median and an end of the sill 11. The sill 12 is formed with a pair of spaced aligned openings 44, 45^a and each opening in sill 12 is arranged between the transverse median and an end of sill 12. The openings 44 are to align and the openings 45^a are to align for a purpose to be referred to.

The combined coupling and bracing members 13, 14 are of like form and each corresponds in construction to any one of the elements 10, with this exception, that they are of less length and of greater height than that of an element 10. Each of the members 13, 14 is formed from a metallic rod having its end terminal portions 45, 46 disposed at right angles to its intermediate portion 47. The latter is of materially greater length than the terminal portions 45, 46.

With reference to Figure 7 there is illustrated by way of example a tool for shifting the sill elements to and from their position (Figure 3) of jacking-up the body sections 8, 9. The tool is indicated generally at 48 and it includes a cross head 49, a pair of oppositely disposed shifting members 50, 51 of angle contour extending over and pivotally connecting at their inner ends with the ends of cross head 49, as at 52, 53, and a lever arm 54 integral at its inner end with and offset with respect to the upper face of cross head 49, as at 55.

70 When using the form, the body sections 8, 9 are arranged in interengaging relation over the base 56 (Figure 2) of the structure which is to be formed. The base 56 is on the bottom of the excavation or on what would be the supporting means for the structure. The body sections 8,

9 are then coupled and braced by the elements 10 which removably engage in the openings of ribs 15, 21. When the body sections are arranged in the position aforesaid, they are disposed upon the sills 11, 12 with the inner part of the bottom edges of the ribs 15, 17 positioned on the lower part of the upper faces of the sills, as is shown in Figure 2. The tool 48 is first engaged in the aligned openings 44 and then operated in either direction on its center whereby the left ends of the sills will be moved to the position as shown at the left of Figure 1 or as shown in Figure 3. The tool 48 is then engaged in the aligned openings 45^a and then operated in either direction on its center whereby the right ends of the sill will be moved to the position shown at the right of Figure 1, at which time the body sections will be jacked up to the position shown in Figures 1 and 3. The length of the lever 54 of the tool 48 is such as to clear the outer ribs of the sets of ribs on the operation of the tool 48. The openings 44, 44^a are spaced inwardly a substantial distance from the end marginal portions of the upper faces of the sills. The outer ribs of the sets are mounted on said marginal portions and the spacing of openings 44, 44^a as aforesaid provide a clearance for lever 54 of tool 48 on the operation of the latter. After the sills have been shifted to the position (Figure 3), the tool is removed and the members 13, 14 are mounted in the opening of the sills. The balance of the structure, indicated at 57 (Figure 3) is then formed. When the structure has been completed, the elements 10 and members 13, 14 are removed, the tool again is used to shift the sills from jacking-up position with respect to body sections 8, 9 which allows for these latter to be lowered. After said sections have been lowered they are separated, after which the sills, elements 10, members 13, 14 and sections 8, 9 are removed from the structure.

What is claimed:

1. A form for the purpose set forth comprising a pair of upstanding oppositely disposed independent body sections having internal coating inherent means to provide for the interengagement thereof in abutting relation at their upper portions of their inner faces and each including internal spaced parallel upstanding ribs carrying an external cheek plank and a set of external crown planks, each of said ribs having its bottom edge inclined downwardly towards its cheek plank, oppositely disposed slideable sills of wedge-like contour for positioning throughout against the bottom edges of and for jacking up said sections in interengaged positions, a set of spaced combined coupling and brace elements transversely disposed relative to said sections and having angularly disposed end terminal portions removably mounted in said ribs, and spaced combined coupling and brace members transversely disposed relative to and having angularly disposed end terminal portions removably mounted in the tops of the sills between the ribs.

2. A form for the purpose set forth comprising a pair of oppositely disposed independent body sections, each including a plurality of parallel spaced upstanding internal ribs, an external cheek plank and a plurality of external crown planks anchored to the ribs, each of said ribs including an inner side edge having its upper portion formed of a pair of spaced endwise aligning superposed straight parts and its remaining portion inclining outwardly from the lower end of the lower one of said straight parts,

each of said sections having its lower side inclining downwardly from its inner side, a pair of bodily slideable oppositely disposed wedge-shaped sills for removably bearing against said lower sides to jack up said sections in upstanding position with straight parts of the ribs of one section abutting straight parts of the ribs of the other section, the inner side edge of each of the ribs of one section being formed with a groove opening between the straight portions thereof, and the inner side edge of each of the ribs of the other section being formed with extensions between the straight parts thereof for seating in said grooves when said sections are jacked up.

3. The invention as set forth in claim 2 having said ribs formed with horizontally disposed apertures adjacent the inclined portions of the inner side edges thereof, said sills formed with vertical openings, a plurality of spaced parallel yoke-shaped combined coupling and bracing elements removably engaging in said apertures, and a plurality of spaced parallel combined coupling and bracing elements removably engaging in said openings.
